UNITED STATES PATENT OFFICE.

JAMES JOLLY, OF BOLTON, ENGLAND.

OPENING MACHINERY FOR TEXTILE FIBERS.

Application filed August 31, 1927. Serial No. 216,768.

This invention relates to opening machinery for textile fibers and is particularly applicable for the opening of hard cotton waste.

Opening machines for hard cotton waste are usually constructed with a lattice feed apron, two pairs of feed rollers to ensure a firm hold of the waste, a cylinder or drum with spikes thereon, a pair of cages, and a lattice delivery apron.

10 In such machines the hard waste is fed by the feed rollers to the rapidly rotating spiked cylinder and is opened whilst being held by the said rollers, after which it is carried to the delivery cages.

15 Such machines have, however, the disadvantage that a certain proportion of the hard waste being treated passes through the machine unopened and the present invention is designed to overcome this disadvantage.

20 According to the present invention a plurality of pairs of feed rollers are arranged at intervals around the periphery of the spiked cylinder, each successive pair being set closer to the spiked cylinder than the preceding 25 pair, and the waste, after being treated at the first pair, is carried to the second pair and, after being acted on by the spiked cylinder whilst being held by the second pair, is carried to a third pair, being finally carried from the final pair to the delivery cages.

25 The invention is illustrated in the accompanying drawing which is a vertical section through an opening machine having three successive pairs of rollers for presenting the fibers to the spiked cylinder.

30 The machine is constructed with a feed lattice A, feed rollers B which receive the fibers from the lattice A, a cylinder C having its periphery covered with spikes or garnett wire clothing and rotating at a relatively high speed and to which the fibers are presented by the feed rollers B, a pair of perforated delivery cages D, and a delivery lattice E, all of which are of usual or known 35 construction.

40 The spiked cylinder C is surrounded by an air tight casing F in communication with a fan G, by the suction of which the fibers, after being operated on by the spiked cylinder C, are removed from the feed rollers B. A guide plate H is arranged in the casing F above the feed rollers B to direct the fibers 45 to a perforated rotating drum J to the in-

terior of which an air duct g, under the influence of the fan G, is connected, so that 55 the fibers are deposited and held by suction on the periphery of the drum J. A semi-cylindrical mask j is arranged in the interior of the drum J so that, as the drum rotates and the fibers are carried round to this 60 masked portion, the suction through the duct g will cease to act on them and they will be delivered to the second pair of feed rollers B¹ which are of smaller diameter than the preceding pair B.

65 This second pair of rollers B¹ again presents the fibers to the spiked cylinder C so that a further opening of the fibers takes place.

70 A second guide plate H¹ is arranged in the casing F above the spiked cylinder C to direct the fibers to a second perforated rotating drum J¹, to the interior of which an air duct g¹, under the influence of the fan G, is connected, so that the fibers are disposed and held by suction on the periphery of the 75 drum J¹.

75 A semi-cylindrical mask j¹ is arranged in the interior of the drum J¹ so that as the drum rotates and the fibers are carried round to the masked portion, the suction of the fan 80 G will cease to act on them and they will be delivered to a third pair of feed rollers B² which are of smaller diameter than the preceding pair B¹. This third pair of rollers B² again presents the fibers to the spiked cylinder C so that a further opening of the fibers takes place.

85 The fibers are then carried by suction in the usual way to the delivery cages D which deliver them to the delivery lattice E.

90 What I claim as my invention and desire to protect by Letters Patent is:—

95 An opening machine for textile fibers comprising a casing having an inlet opening at one end and an outlet opening at its opposite end, a drum rotatable in said casing and having spikes projecting from its periphery, means in said inlet opening to receive textile fibers and deliver same to said drum, a plurality of perforated cylindrical cages in 100 said casing spaced around the periphery of said drum and rotatable in the same direction as said drum with their peripheries in close proximity to the outer ends of the spikes of said drum, means for creating suction in 105 said cages, a plurality of pairs of feed rollers,

each of said pairs of rollers being mounted adjacent the periphery of one of said cages and in close proximity to the outer ends of the spikes of said drum and adapted to receive fibers directly from their associated cage and deliver same directly to the spikes of said drum, each of said cages having a

fixed mask mounted therein opposite the pair of feed rollers associated therewith for shutting off suction through the perforations of such cage opposite such feed rollers.

In testimony whereof I have hereunto set my hand.

JAMES JOLLY.
